GEORGE W. DONNING, OF STAMFORD, CONNECTICUT, ASSIGNOR TO DONNING CARBURETER CORPORATION, OF ESOPUS, NEW YORK, A CORPORATION OF NEW YORK.

CARBURETER.

1,258,881.

Specification of Letters Patent. Patented Mar. 12, 1918.

Application filed January 5, 1916. Serial No. 70,485.

To all whom it may concern:

Be it known that I, GEORGE W. DONNING, a citizen of the United States, residing at Stamford, in the county of Fairfield and 5 State of Connecticut, have invented certain new and useful Improvements in Carbureters, of which the following is a specification, reference being had therein to the accompanying drawing.

This invention relates broadly to carbureters and more especially to means for increasing the efficiency thereof.

The primary object of the invention is to simplify the construction of a carbureter 5 by coöperatively aggrouping certain adjustable features and parts (now usually remotely separated) and, thereby, making the construction conveniently manipulated, and increasing its efficiency and durability.

Another object is to provide automatic 10 means for operating the air and fuel valves within certain and known limits, so that as the degree of suction of the motor becomes less, the valves will assume new positions irrespective of the adjustment of the carbureter-throttle, thus tending to reduce the 15 flow of fuel and air with resultant reduction to a minimum of the danger of flooding of the carbureter.

Another object is to provide means, preferably in the form of a thermostatic device, to effect an automatic regulation of certain 20 valves in the carbureter, in conjunction with the means for developing a counteraction to the thermostatic device, such means also operating to effect a simultaneous operation of the pet-cock of the fuel-nozzle, whereby it may be positioned for permitting the introduction 25 of one or another kinds of fuel into the carbureter.

The invention in general seeks to provide a structure of simple organization and one well adapted to meet the requirements of varying climatic conditions and is especially 30 useful in automobiles, aeroplanes, motor-boats, etc.

The invention resides, generally, in the structure, and in the details thereof, as hereinafter described.

That the invention may be readily comprehended, I have illustrated a preferred embodiment thereof in the appended drawings forming a part of this disclosure, but

which are to be understood as illustrative merely and not as indicative of the limits of 55 the invention.

In these drawings:

Figure 1 is a view in central vertical section of a carbureter including an embodiment of my invention, and as adapted particularly for use in connection with a motor, 60 not shown;

Fig. 2 is a fragmentary view in elevation thereof;

Fig. 3 is a fragmentary view in top plan 65 of the same, parts being broken away more clearly to show certain details;

Fig. 4 is a view in horizontal section on the line 4—4, Fig. 1;

Fig. 5 is a view in detail of a fuel and air 70 controlling device forming a part of the carbureter structure; and

Fig. 6 is a view in detail, in section, on the line 6—6, Fig. 5.

Referring to the drawings, it will be observed that the reference-character 1 designates, generally, the casing of a carbureter proper; 2 designates, generally, the casing of a manifold head connected to the carbureter into which the motor inlet manifolds 80 3 lead; and 4 designates an air conduit or heating box connected to and leading into the lower portion 5 of the carbureter, and which houses an extended, coiled portion 85 of the exhaust 6.

The carbureter casing is divided into a mixing chamber 7 and an air inlet or chamber 8. The outflow of gaseous mixture from the chamber 7 is controlled by a throttle-valve 9 mounted on a shaft 10 which is 90 operated in the usual manner.

Leading into the air inlet 8 is a fuel-nozzle 11 provided exteriorly with a helical ridge 12 to catch any of the fuel that may overflow the discharge end 13 of the nozzle. 95 The nozzle is formed with a channel 14 with which a Y-coupling 15 communicates, and which is provided with a two-way valve 16 adapted to control fuel-channels 17 and 18, and which provides means for 100 introducing these two different grades or kinds of fuels, such as gasoline (through the channel 17) or kerosene (through the channel 18). In the channel 14 is disposed a guide-block 19 provided with one or more 105 passages 20 through which the fuel flows

from the coupling 15 into the channel 14. The nozzle is controlled by a tapered valve member 21 which has an elongated stem 22 that is guided in a bore 23 formed in the 5 guide-block 19. The valve member 21 carries at its upper end a cap 24 which has a sliding movement in relation to the valve member 21, and which movement is limited by a yoke-piece 25 which extends through 10 and is moved by the cap and embraces a reduced portion 26 of the valve member, as clearly shown in Figs. 5 and 6, and is adapted to abut against the head 26^a on the upper end of the valve-member 21 when the lever 15 30, through the action of the throttle 9, is raised sufficiently high. Upstanding from and integral with the cap is a bifurcated extension 27 carrying a cross-pin 28 adapted to move in an arcuate slot 29 formed in one 20 arm of a three-armed lever 30. One arm of this lever is pivotally connected to a slide-element 31 which is movably mounted in a screw-plug 32 threaded into the carbureter-casing 1, and projects beyond the outside 25 face of this plug and is provided with a manipulating-head 33. The guide-element is provided with a plurality of holes or recesses 34 into which a locking-pin 35 is adapted to project and thereby retain the 30 slide-piece in any of a plurality of adjustable positions, the locking-pins being threaded into the screw-plug 32, as shown in Fig. 1. Pivotally connected to another arm of the lever 30 is a link 36 which, at 35 its upper end, is pivotally connected to the throttle-valve 9. Sustained by a boss 37 formed on the valve-member 21 is an air-constrictor or disk 38, which, in this instance, is secured to the boss, though it 40 may, in some embodiments, be loosely carried thereby. The constrictor normally seats on the upper end of the wall 39 which forms a part of the air inlet 8. Interposed between the lower end of the cap 24 and 45 the constrictor 38 is a spring 40, having a normal tendency to displace the constrictor 38 and the valve 21 away from the cap when the throttle-valve 9 is actuated.

Threaded into the carbureter casing, opposite the plug 32, is a second plug 41—and which is interchangeable with the plug 32—and in which is seated pressure-relieving valve-member 42 movable outwardly, such movement being limited by a screw or pin 43 projecting from the plug into a slot or recess 44 formed in one of three guide-extensions 42^a in the valve. The valve is retained in position by a spring-pressed lever 45 pivoted on the outside of the carbureter 50 casing, and which is also operable, manually, by a wire 46, here shown as broken off.

Encompassing the carbureter casing 1 is a jacket 47 (of suitable non-conducting material and incased by a metallic protector) 55 which provides channels 48 into which a

heating fluid, such as hot water, may be introduced to effect an initial warming of the carbureter and its contents. A drain-cock 49 is provided in the lower section of the casing to drain the channels. The heating 70 fluid may be introduced into the channels through a capped elbow 50 (Fig. 3) mounted at the upper portion of the carbureter.

The manifold head 2, sustained by the carbureter casing 1, is divided into a commingling chamber 51 and a thermostatic chamber 52. Interposed between the chambers is a reticulated element 53 held in place by lugs 54 extending inwardly from the walls of the casing. 75

The motor inlet manifolds 3 are provided with flaring ends 55 which are held by correspondingly formed walls 56 of screw plugs 57 that are threaded into the manifold head casing 2, and whereby the carbureter, in its entirety, is rigidly locked to the motor inlets 3 which are, as usual, connected to a motor, not shown. In other words, the motor inlets 3 sustain the carbureter, and avoid the necessity of providing flanges, supporting brackets and the like for the carbureter. 85

Threaded into the manifold head 2 is a screw cap 58. Screwed into a depending portion of the screw-cap is a thermostat casing 59. Housed within the casing 52 is a guide-member 60 provided with an elongated bore 61 in which is mounted a plunger 62. The upper portion of the member 60 is recessed, as at 63, for the reception of packing or the like. The plunger 62 is provided with circumferential grooves 64. Housed within the casing 59 is an expandible substance 65, such as a volatile fluid adapted, by its expansion, to actuate the plunger 62. 100 As shown, the volatile fluid only partially fills the casing, the unfilled portion 66 thereof containing air or the like, and which operates with the volatile fluid to cause the expansive action to actuate the plunger, as 105 already mentioned. Upstanding from the casing 2 is a post 67 on which is fulcrumed a lever 68 that is pivotally connected to the upper end of the plunger 62 and, at its opposite end, to a link 69 which, in turn, is connected to a boss 70 upstanding from a valve member 71 which controls a port 72 formed in the air-inlet 8. The valve-member 71 is secured to a shaft 73 journaled in the walls of the air inlet 8. The shaft extends beyond 110 the outside surface of the walls of the air inlet and has secured thereto a link 74. Connected at one end to the link 74 is a second link 75, which, at its opposite end, is pivotally connected to a third link 76 fast on a 115 shaft 77 journaled on the inside wall of the air inlet 8, and upon which is mounted a valve-member 78 adapted to control a port 79 which, in this instance, communicates with a cold-air conductor 80, which extends 120

125

130

to a point remote from the motor whereby the coldest possible air, uninfluenced by the heat of the motor, may be secured.

Threaded into the manifold head 2 is a capped cup 81, by means of which gasoline or the like may be introduced into the chamber 52 for initial priming purposes.

Loose on the shaft 73 is a collar 82 (Figs. 2 and 3) and fast to this collar is an actuating arm 83. Pivotaly connected to the actuating arm is a link 84 which, at its opposite end, is pivotaly connected to a link 85 carried by a stem 86 on which is mounted the two-way valve 16.

Attached to the collar 82 is an elongated curved spring 87 normally pressing lightly against the valve member 71, as shown in Fig. 2, but which is tensionable by the valve-member when the same is operated, in the manner presently to be described.

Operation: Assuming that the atmospheric conditions are moderately cold, that is, about at freezing temperature, a limited amount of gasoline may be introduced through the cup 81 into the chamber 52, for initial priming, in the usual way. If, however, the atmospheric conditions are nearer zero or below, a heating fluid, such as hot water, may be introduced through the capped elbow 50 into the channels 48, whereby the carburetor and its contained instrumentalities may be given an initial warming. For ordinary temperatures, from 50° up, the initial priming or warming may be omitted.

If gasoline, for example, is to be utilized in the carburetor, the actuating arm 83 is moved so as to permit the gasoline to flow through the channel 17 from a suitable source of supply (not shown) and through the passages 20 into the channel 14, wherein it is retained by the valve 21, the latter being in its closed position. Then, the throttle-valve is opened to "starting position" of the motor. The movement of the valve will, through the link 36 and lever 30, raise the cap 24, thus permitting the expansion of the spring 40 and, owing to the lost motion permitted between the cap 24 and the portion 26 of the valve-member 21, the latter and the air-constrictor will, by their own weight, remain seated.

The motor having been started, it will create a suction through the carburetor, and this will raise the air-constrictor and the valve against the spring 40 and thereby open the fuel-nozzle for the outflow therethrough of the fuel which has been housed in the channel 14. The air passing through the air inlet 8, under the suction aforementioned, commingles with the fuel in the mixing chamber 7 and the resulting mixture then passes by the throttle 9 into the commingling chamber 51, and thence into the chamber 52 where it will be effective upon

the contents of the thermostat casing 59 before it passes into the motor manifolds 3 and thence into the motor. Obviously, when the throttle-valve 9 is opened wider, it will, through the link 36 and lever 30, raise the cap 24 so that the yoke 25 will engage the head 26^a and raise the fuel-valve 21, thus moving it beyond the limit of the lost-motion of the cap on the upper end of the fuel-valve and thereby effect a lifting-action of both the fuel-valve and the valve 38 to permit an increased volume of fuel and air to enter the mixing-chamber. The ignition of the mixture in the motor, with resultant outflow therethrough of the heated gases 30 into the exhaust 6, effects a heating of the air within the heating box 4—the coiled form of the extension providing for an enlarged heating area within the heating box. The temperature of the air in the heating 85 box 4 being gradually raised, due to the heating action of the coils, passes into the air-intake 8 and thereafter will be utilized to combine with the fuel to produce an effective gaseous mixture. The rising temperature of the air naturally makes the same more effective upon the thermostatic device. When such temperature has reached a predetermined degree, the thermostatic device will become operative and the plunger 62 90 thereof will, under the influence of the thermostatic fluid, be raised to actuate the lever 68 and link 69 to open the valve-members 71 and 78. The flow of heated air through the heating box 4 is checked by the 100 inflow of cold air through the port 80 into the air-inlet 8. The inward movement of the valve-members 71 and 78 produces either a partial or complete closure within the portion 5 and partly or completely checks the 105 flow of heated air thereinto from the heating box 4, such heated air then passing out through the port 72.

When, however, the air in the air-inlet has become sufficiently chilled to reduce the 110 temperature within the chamber 52 and thereby cause the volatile fluid to recede, with a resultant dropping of the plunger 62—such movement being accelerated by the spring 87—the latter will effect an actuation 115 in the opposite direction of the lever 68 and link 69 to close the valve-members 71 and 78, whereupon heated air from the heating box 4 will pass into the air-inlet 8, thence into the mixing chamber 7, and thence 120 into the chamber 52. The opening of the valve-member 71, pressing against the spring 87, tensions it so that it will react, when the thermostatic plunger 62 drops, to close the valve-members 71 and 78.

If kerosene is to be utilized in the carburetor, the actuating arm 83 is moved to open the valve for the inflow of the kerosene through the channel 18 and to close the channel 17. The movement of the arm 83 130

1 forces the spring 87 against the valve-member 71 to increase its tension. In consequence, the force required to open the valve-members 71 and 78 is increased. Therefore, 6 a higher temperature of the mixture in the chamber 52 will be required to influence the thermostatic device for actuating the plunger 62. Kerosene, being of lower specific gravity, requires a higher heat to effect 10 vaporization in the mixing chamber 7; consequently, the thermostatic device must not actuate as soon as it does where gasoline is employed. The retarded movement of the thermostatic device and, thus, of the valve-members 71 and 78, permits the air from the heating-box 4 to be raised to a higher degree before passing into the air-inlet 8 because it is not checked by the inflow of cold air through the port 79.

20 As a guide to the operator, the indicating symbols "G" and "K"—indicative of "gasoline" and "kerosene," respectively—may be placed on the side of the carburetor in juxtaposition to the relative positions of the 25 actuating arm 83. It is to be understood that the operation of the actuating arm 83 to tension the spring 87 simultaneously operates the coupling-valve 16, thus insuring the introduction of the desired fuel—gasoline or kerosene—to correspond with the 30 adjustment of the temperature-control, comprising the thermostatic device and the parts operated thereby. In the absence of a connection between the actuating-arm 83 and 35 the coupling-valve, the operator might inadvertently set the temperature-control for the wrong kind of fuel.

In the event of a preignition of the mixture and a back-firing of the carburetor, and 40 in order to relieve the consequent strain upon the air-constrictor 38, etc., the valve 42 is blown outwardly and thereby reduces the pressure within the mixing-chamber 7. Moreover, the lost motion permitted between 45 the cap 24 and the valve 21 permits such pressure to actuate the constrictor 38 and thereby seating the constrictor and the fuel-valve 21, shutting off the flow of fuel and thus preventing the ignition of fuel 50 within the carburetor. This obviates the danger of fires within the carburetor, which nowadays are quite common in other types of carburetors. In the event that the operator desires to add more air to the mixing- 55 chamber 7 to thin the mixture therein, he may, by the wire 46, open the valve 42 for this purpose.

Initially to adjust the carburetor for proper action in conjunction with the motor, the setting of the slide member 31 changes the fulcrum point of the lever 30 so that the operation of the throttle-valve 9 effects a greater or less movement of the fuel and air-valves 21 and 38, respectively. 60 When once adjusted, the slide is locked by

the pin 35, and such adjustment will suffice indefinitely: Any change of climatic condition is taken care of by the thermostatic device, thus insuring the inflow into the mixing-chamber of a fairly even tempered air 70 under all conditions, which obviates the necessity of increasing or decreasing the amount of fuel, as usual.

From the foregoing, it will be perceived that I have succeeded in devising a carburetor-structure which is well adapted to achieve the several objects and ends in view. The structure is simple and compact in form, and it is so constructed as to permit of its ready application to existing forms of engines.

In the event that a given motor is running "light", that is, free of load, the tendency of the motor would be to increase in speed and, thus, the suction of air about valve 38 95 is increased. This would lift the valve against the tension of the spring 40, irrespective of any predetermined adjustment of the throttle-valve 9; but, the moment that the load or work is imposed on the motor, the tendency of the motor would be to slacken and, to avoid a waste of fuel, the constrictor is designed (through action of the spring 40 and its weight) to lower the fuel-valve 21 into the nozzle 11, thus reducing the quantity of fuel flowing therefrom.

As many changes can be made in the construction and many widely different embodiments of the invention can be made without departing from the spirit thereof, it is intended that all matter contained in the foregoing description and shown in the accompanying drawings shall be interpreted as illustrative and not in any limiting sense, 105 and that the language employed in the following claims is intended to cover the generic as well as the specific features of the invention.

What I claim is:

1. A carburetor including a chamber, a throttle-valve for controlling the passage through the chamber, connected fuel and air valves, a connection between the throttle-valve and the connected valves whereby the latter may be operated by the throttle-valve, and means interposed between the throttle and connected valves whereby the latter may have movement independently of the throttle-valve.

2. A carburetor including a chamber, a throttle-valve for controlling the passage through the chamber, connected fuel and air valves, a connection between the throttle-valve and the connected valves whereby the latter may be operated by the throttle-valve, means interposed between the throttle and connected valves whereby the latter may have movement independently of the throttle-valve, and means having a normal 125

tendency to displace the connected valves away from the throttle.

3. A carbureter including a chamber, a throttle-valve at one end thereof, air and fuel-controlling valves operatively associated with the throttle-valve, and means including a lost-motion connection between the controlling-valves and the throttle-valve and operable to effect coaction between the 10 throttle, on the one part, and both the air and fuel-controlling valves, on the other whereby movement of the throttle-valve will actuate the controlling valves and whereby also limited movement of the controlling valves independently of the throttle-valve is permitted.

4. A carbureter including a chamber, a throttle-valve therein, connected fuel and air controlling valves, means active thereon 20 for effecting their movement away from the throttle-valve, and means connected to the throttle and connected valves for lifting the latter.

5. A carbureter including a chamber, a 25 throttle-valve therein, air and fuel controlling valves, means including a resilient instrumentality for effecting relative movement between the throttle-valve and the controlling valves, and an adjusting device 30 common to the throttle and the controlling valves and extending beyond the walls of the chamber and operable outside of the carbureter for varying the extent of movement of both the air-controlling valve and 35 the fuel-controlling valve relatively to the movement of the throttle-valve.

6. A carbureter including a chamber, a 40 throttle-valve therein, an air-controlling valve, a fuel-controlling valve, means operatively associated with the throttle-valve and with the air and fuel-controlling valves and including an adjusting device common 45 to the throttle and the controlling valves and extending beyond the walls of the chamber and operable outside of the carbureter for varying the extent of movement of the air and fuel-controlling valves simultaneously and relatively, and resilient means 50 for governing movement of the controlling valves.

7. A carbureter including a chamber, a 55 throttle-valve therein, an air-controlling valve, instrumentalities disposed entirely within the carbureter-chamber for co-actively connecting the throttle and air-controlling valves, means including a slideable adjusting device common to both valves for varying the extent of movement of the air-controlling valve relatively to the movement 60 of the throttle-valve, and means for retaining the slideable device in any of a plurality of operative positions.

8. A carbureter including a carbureter-chamber, an air-chamber, a yieldable valve-member interposed between the chambers,

a fuel-nozzle in the air-chamber, a fuel-controlling valve operative in the fuel-nozzle and operatively associated with the yieldable valve, a throttle-valve operatively associated with the yieldable valve, and means 70 interposed between the throttle-valve and yieldable valve whereby, when the throttle-valve is actuated, the yieldable and fuel-controlling valves are likewise operated.

9. A carbureter including a mixing-chamber, a juxtaposed air-chamber, a yieldable valve between the chambers for controlling the flow of air from the air-chamber into the mixing-chamber, a fuel-nozzle extending into the air-chamber, a fuel-controlling 80 valve adapted to be seated in the fuel-nozzle and operatively associated with the yieldable valve, a throttle-valve for controlling the outflow of the contents of the mixing-chamber, a connection between the throttle-valve and the yieldable valve including a valve-sustaining arm, and a slide member connected to the arm for positioning it in relation to the axis of rotation of the throttle-valve.

10. A carbureter including a mixing-chamber, an air-chamber, means for controlling the flow of air from the air-chamber to the mixing-chamber including a yieldable plate, a throttle-valve, and connecting 95 means between said throttle-valve and said yieldable plate including a shiftable arm and a slide-member for manually moving said arm.

11. A carbureter including a mixing-chamber, an air-chamber, means for controlling the flow of air from said air-chamber into said mixing-chamber including a valve-device comprising a yieldable plate, a throttle-valve for controlling the outflow 105 of a gaseous mixture from said mixing-chamber, and means for actuating said yieldable plate comprising a shiftable arm, a link between the arm and the throttle-valve, and a manually-operated slide-member 110 connected to the arm.

12. A carbureter including a chamber, a throttle-valve at one end thereof, an air-controlling valve at one side of and actuatable by the throttle-valve, a fuel-valve associated with and actuatable by the throttle-valve, a fuel-nozzle controlled by the fuel-valve, and means interposed between the throttle and air-controlling valves and tending to displace the air-controlling valve 120 away from the throttle-valve.

13. A carbureter including a chamber, a throttle-valve for controlling a gaseous mixture therefrom, an air-controlling valve connected to the throttle-valve but having 125 movement in one direction independently thereof under the influence of a suction-action in the chamber, a fuel-valve also connected to the throttle-valve and in relation to which throttle-valve the air-controlling 130

valve has independent movement, whereby the flow of air into the chamber may automatically be augmented without operation of the throttle-valve, and a connection disposed within the carbureter-chamber and associated with the air-controlling valve and the fuel-valve for unison of action thereof in one direction.

14. A carbureter including a chamber, a throttle-valve for controlling the flow therefrom of a gaseous mixture, an air-controlling valve, connecting means between the valves whereby the air-controlling valve is actuated in one direction simultaneously with the throttle-valve, yieldable means between the throttle-valve and the air-controlling valve, whereby the air-controlling valve may have movement in one direction independently of the movement or position of the throttle-valve, and a fuel-controlling valve actuatable by the throttle-valve and associated with the air-controlling valve

and operable thereby when the same is actuated under the influence of a suction-action in the chamber.

25

15. In a carbureter, a chamber therein, a throttle-valve for controlling flow therefrom of a gaseous mixture, a flexible air-controlling device for governing the passage of a fluid into said chamber and adapted to be actuated by a suction action within the chamber, a fuel-nozzle extending into the carbureter, a fuel-controlling valve therein connected to the air-controlling device, and connections between the throttle-valve, the air-controlling valve, and the fuel-controlling valve for effecting unison of action of these valves.

In testimony whereof I affix my signature in presence of two witnesses:

GEORGE W. DONNING.
